UNITED STATES PATENT OFFICE.

ELVER H. SHAW, OF SEDALIA, MISSOURI, ASSIGNOR OF ONE-HALF TO
W. A. FRASER, OF SAME PLACE.

COMBINATION-TOOL.

SPECIFICATION forming part of Letters Patent No. 606,395, dated June 28, 1898.

Application filed December 31, 1897. Serial No. 664,949. (No model.)

To all whom it may concern:

Be it known that I, ELVER H. SHAW, a citizen of the United States, residing at Sedalia, in the county of Pettis and State of Missouri, have invented a new and useful Combination-Tool, of which the following is a specification.

The invention relates to improvements in combination-tools.

The object of the present invention is to improve the construction of combination-tools and to provide a wrench adapted to be converted into a brace and capable of being mounted upon a bench and of serving as a vise.

The invention consists in the construction and novel combination and arrangement of parts, as hereinafter fully described, illustrated in the accompanying drawings, and pointed out in the claims hereto appended.

In the drawings, Figure 1 is a perspective view of a combination-tool constructed in accordance with this invention. Fig. 2 is a side elevation, the parts being arranged to form a brace. Fig. 3 is a sectional view, the parts being arranged to form a vise. Fig. 4 is a longitudinal sectional view, the parts being arranged as shown in Fig. 1. Fig. 5 is a detail view of the shank.

Like numerals of reference designate corresponding parts in the several figures of the drawings.

1 designates a shank receiving a sliding jaw 2, which is adjusted to and from a stationary jaw 3 by means of an adjusting-screw 4. The 35 sliding jaw is provided with a rectangular opening for the shank 1, and the fixed jaw, which is detachably secured to the outer end of the shank, is provided with a corresponding opening and is adapted to be removed to 40 permit the parts to be separated and assembled, as the inner end is enlarged for a purpose hereinafter described and will not permit the sliding jaw to be introduced on the wrench from that end. Any suitable means 45 may be employed for detachably fastening the stationary jaw 3 to the outer end of the shank 1.

The rear end of the stationary jaw is provided with a claw 5 for extracting nails, and 50 the engaging faces 6 and 7 of the jaws are provided with longitudinal grooves, angular in

cross-section and adapted to receive the shank of a screw-driver, auger, or similar tool when the device is arranged to operate as a brace. The adjusting-screw 4, which operates the 55 sliding jaw, is swiveled to an oblong collar or loop 8 and is provided at one end with a milled head. The inner portion of the screw 4 is smooth and passes through a corresponding perforation of the loop or collar 8, and the 60 upper or outer portion, which is connected with the movable jaw, is threaded and engages a threaded opening of the same. The screw is provided with a suitable stop or collar which engages the loop 8 to form a stop 65 and prevent the screw from moving longitudinally, the loop being arranged between the milled head and the stop of the screw. The loop 8 is arranged upon an enlarged portion 70 of the inner end of the shank, and the latter is provided at the outer edge of the enlarged portion 9 with a laterally-offset rectangular ear 10, which forms an inner shoulder against which the loop or collar abuts. The loop or collar 8 is provided at its back 75 with a rearwardly-extending lug or projection 11, adapted to fit in an opening of a bench to support the device when the same is arranged to form a vise, as hereinafter described. The lateral offsetting of the perforated ear 10 also provides a shoulder 12 at the outer edge of the enlarged portion 9, and a crank-handle 13, which is detachably connected with the perforated ear by a suitable fastening device 14, is adapted to abut against 85 the shoulder 12, whereby it is rigidly secured to the shank by the single fastening device 14.

The crank-handle 13 is composed of inner and outer arms 15 and 16, detachably connected by a fastening device 17 and adapted 90 to be separated, so that the inner arm 15 may form an extension of the shank when it is desired to use the device as a simple wrench. The inner end of the arm 15 is recessed to receive the perforated ear and is adapted to 95 abut against the outer edge of the same as well as against the shoulder 12. The inner arm is provided with a rotary grip 18, arranged on the rounded portion of the arm, and the other arm 16 is provided at its outer end with a 100 breastplate or rest 19, which is also pivotally mounted, so that the device, when ar-

ranged as illustrated in Fig. 2 of the accompanying drawings, may operate similar to an ordinary brace.

When it is desired to use the device as a vise, the crank-handle is entirely removed from the shank and the rest of the device is arranged as illustrated in Fig. 3 of the accompanying drawings, the lug or projection 11 being fitted in a suitable opening or socket of

10 a bench.

The invention has the following advantages: The combination-tool is simple and comparatively inexpensive in construction and is adapted to be readily arranged to form 15 a wrench, a brace, or a vise. It is adapted for extracting nails and it is capable of gripping an ordinary bit.

Changes in the form, proportion, and minor details of construction may be resorted to 20 without departing from the spirit or sacrificing any of the advantages of this invention.

What I claim is—

1. In a device of the class described, the combination of a shank provided with a shoulder or stop, a stationary jaw, a movable jaw, a collar or loop arranged on the shank and abutting against the shoulder or stop, said collar or loop being provided with a lug adapted to fit in an opening or socket of a bench, 25 and means for adjusting the movable jaw, substantially as described.

2. In a device of the class described, the combination of a shank provided at its inner end with an enlarged portion and having a 30 perforated ear 10 laterally offset to form a shoulder 12, a stationary jaw detachably secured to the outer end of the shank, an adjustable jaw, means for operating the latter,

a crank-handle provided at its inner arm with a perforation, said inner arm being adapted 40 to be arranged longitudinally of the shank and at right angles to the same and to fit against the said shoulder 12 in both positions, and a fastening device passing through the perforations and detachably securing the 45 crank-handle to the shank, substantially as described.

3. In a device of the class described, the combination of a shank having one end enlarged and provided beyond the enlarged portion with a laterally-offset ear forming a shoulder, a movable jaw, a detachable stationary jaw, a collar or loop arranged on the enlarged portion of the shank and provided with a lug adapted to fit in an opening or socket of a 55 bench, and means for adjusting the movable jaw, substantially as described.

4. In a device of the class described, the combination of a shank enlarged at one end and provided with a laterally-offset ear forming a straight inner shoulder, a loop arranged on the enlarged portion of the shank, fitting against the said shoulder and provided with a lug, a sliding jaw, a stationary jaw, and a crank-handle detachably and adjustably connected to the ear of the shank and fitting against the outer edge of the said enlargement, substantially as described.

In testimony that I claim the foregoing as my own I have hereto affixed my signature in 70 the presence of two witnesses.

ELVER H. SHAW.
